NECKTIE SMOOTHER

George N. Phelps, East Haddam, Conn.

Application May 16, 1940, Serial No. 335,527

5 Claims. (Cl. 223—63)

My invention relates to the class of devices which are employed for preserving the shapes of neckties to retain them in unwrinkled condition, and an object of my invention, among others, is to provide a device of this sort that shall be simple in construction, that may be readily inserted through a necktie, and that shall efficiently maintain the necktie in an unwrinkled condition.

One form of a necktie holder and smoother embodying my invention and in the construction and use of which the objects herein set out, as well as others, may be attained is illustrated in the accompanying drawing, in which—

Figure 1 is a face view of a holder embodying my invention with a necktie illustrated in dotted lines on the holder.

Figure 2 is a similar view on enlarged scale showing the branches of the holder latched together.

Figure 3 is a similar view of the holder but illustrating the ends of the branches disengaged as when in a tie.

Figure 4 is a view looking at that end terminating the branches.

Figure 5 is a view in section on a plane denoted by the dotted line 5—5 of Fig. 2.

Figure 6 is a view on enlarged scale illustrating the manner of retaining the branches in engagement.

Figure 7 is a similar view showing the branches disengaged.

Figure 8 is a view illustrating means for securing the ends of the spring to the body of the holder.

My improved holder as illustrated and described herein comprises a body adapted to engage within the wider part of a necktie, this body gradually decreasing in width to the smaller end which is inserted within the tie and retained in the narrower portion thereof. This holder is constructed of wire and is provided with spring qualities to retain the body of the holder in its operative form to exert a slight outward pressure against a necktie to remove any wrinkles that may exist therein and to retain the tie in a smooth condition.

In the accompanying drawing the numeral 8 denotes the side parts of the body of the holder which is composed of wire having spring qualities and which is bowed outwardly at the widest portion but which terminates in a rounded end 9. The holder is composed of a single piece of wire, the side parts comprising the body being extended into branches 10—11 forming the narrow portions of the holder and terminating in a

bluntly pointed or small rounded end 12. The ends of the branches are removably engaged one with the other, the end of one branch 10 having a lip 13 with a locking lug 14, and the end of the other branch 11 having a lip 15 with a hole 16, said lip and hole constituting a keeper to receive the lug 14 and thereby retain the ends of the two branches in removable locked engagement. The branch 10 of the holder is slightly longer than the branch 11, as shown in Fig. 3, and when this end of said branch 10 is forced lengthwise to engage the lug 14 with its keeper the tendency of the branch to assume its normal longer condition will exert a force lengthwise of the holder to securely retain the engagement of said lug and keeper.

This holder being advantageously constructed of comparatively light wire in order to obtain a light structure, means are provided for retaining the holder and particularly the body part in its original form. As shown herein this form retaining means comprises a spring 18 preferably coiled and with branches 19 extending from opposite sides of the coil. I have found that a turn and a half of the coil 18 will be sufficient to accomplish its purpose in exerting an outward force on the side parts of the body to retain them in their original form. The ends 20 of the branches are secured to the side parts 8 in any suitable manner, spot welding 21 being shown herein for this purpose.

The form retainer comprising the spring 18 and its branches 19 hereinbefore referred to is extended backwardly from the ends 20 of said branches and is located within the bend of the rounded end 9, as shown in Figs. 1 and 2. This bend constitutes a housing for the form retainer so that it will not interfere in the operation of inserting the holder within a tie and in removing it therefrom.

The locking engagement of the free ends of the branches at the small end of the holder provides a structure that is of particular advantage when the holder is not in use as it may be laid away in a drawer or similar place or may be hung upon a hook and the ends being locked together will not catch upon articles of clothing or other material as they would otherwise if allowed to spread apart, and there is therefore provided means for eliminating a condition that might otherwise prove troublesome.

In use the free ends are unlocked, as shown in Fig. 3, the holder in this form being a little wider than the ordinary tie so that a slight spreading action will exist to preserve the tie substantially

in the form shown in dotted lines in Fig. 1, it not being intended, however, that an extreme stretching action will take place.

In accordance with the provisions of the patent statutes I have described the principles of operation of my invention, together with the device which I now consider to represent the best embodiment thereof; but I desire to have it understood that the device shown is only illustrative and that the invention may be carried out by other means and applied to uses other than those above set out.

I claim:

1. A necktie smoother composed of a single piece of wire bent to oval shape to form the rounded end of a body which is gradually tapered into a narrower portion comprising branches having free ends, means for removably securing said ends together, and a spring housed within said rounded end of said body, said spring having branches, the whole conforming in shape to the rounded end and sides of said body and of a width substantially that of the space between the sides of said body, said spring branches being secured at their free ends to the sides of said body to exert outward pressure between the sides of the body to preserve its form.

2. A necktie smoother composed of a single piece of wire bent to oval shape to form the rounded end of a body which is gradually tapered into a narrower portion comprising branches having free ends, interlocking means upon said free ends for removably securing them together, and a spring form preserver comprising a coiled spring housed within said rounded end of the body and having branches extending from the coil parallel with the sides of the body and spaced therefrom, the extremities of said

ends being bent abruptly outward and then parallel with each other, the parallel parts being secured to the sides of the body.

3. A necktie smoother composed of a single piece of wire bent to oval shape to form the rounded end of a body which is gradually tapered into a narrower portion and which is composed of branches having free ends, lips formed on said ends, an interengaging lug and opening on said lips, and means secured between the sides of said body and housed within the rounded end thereof and exerting outward pressure between the sides of the body to preserve its form.

4. A necktie smoother composed of a single piece of wire and comprising a body with side branches bent to oval shape to form the rounded end of said body which is gradually curved to a narrower width terminating in a narrow rounded portion one of the branches being longer than the other, lips formed on the ends of said branches, an interengaging lug and opening on said lips, said oval shaped branches exerting force to retain said lug in said hole, and means secured between the sides of the body and housed within the oval shaped end thereof and secured to its sides to exert outward pressure between said sides to preserve the form of the body.

5. A necktie smoother composed of a single piece of wire bent to oval shape to form a body which is gradually tapered toward one end into a narrower portion, said body end comprising branches having free ends, interlocking means on said free ends for removably securing them in close engagement, and a spring form preserver comprising a coiled spring at the end of said body opposite said free ends for forcing said branches apart to preserve the form of a tie.

GEORGE N. PHELPS.
